[57] ABSTRACT

A miniature electrical reversing switch is disclosed for a power tool trigger switch wherein separate pairs of fixed contacts in the switch circuitry are selectively bridged by bridging contactors to reverse current flow therefrom to the tool motor. The contactors are mounted on a movable slide member which is part of a compact one-piece integral plastic molding also including an integral flexible hinge and external knob operator.

The knob operator is mounted concentric with the trigger lock pin bushing and is manually rotated about the base thereof for coaction with the flexing hinge to impart linear sliding action to the slide and bridging contactors relative to the fixed contacts.

**MINIATURE ELECTRICAL REVERSING SWITCH
MOUNTED ON TRIGGER OPERATED SWITCH
FOR HAND-HELD TOOLS**

BACKGROUND OF THE INVENTION

This invention generally relates to electrical reversing switches for power tools and the like and more particularly to improvements therein that contribute to miniaturization of such switches and economies of manufacture.

Various switches have been devised for power tools and household appliances to reverse the direction of rotation of the electric motor for such devices. By way of background, it may be observed that the manufacture of these switches is exceedingly competitive necessitating that cost thereof be kept to an absolute minimum. At the same time, however, manufacturers of such switches are called upon by their customers to supply switches of improved quality as compared to switches used in the past. Moreover, in addition to cost considerations, existing switches are generally complicated and bulky requiring a considerable amount of space within the tool.

Consequently, the design of reversing switch constructions has been an extremely active field in recent years, the primary aim of this activity being to improve such switches by reducing the number of required component parts and by making them smaller, more durable and dependable and less costly and adaptable to applications having certain size limits.

SUMMARY OF THE INVENTION

The general object of the present invention is to provide an improved reversing switch of the type described which circumvents the problems heretofore noted as well as other disadvantages of the prior art.

More specifically, it is an object of this invention to provide a durable miniature electrical reversing switch for tools and appliances which is capable of manufacture at low cost, has a minimum number of parts and so designed to be readily and easily assembled in mass production operation.

These and other objects and advantages will become more apparent in the following specification and claims when read in conjunction with the appended drawings.

DETAILED DESCRIPTION OF THE DRAWINGS

In describing the present invention, reference will be made to the accompanying drawings forming a part of the instant invention wherein:

FIG. 1 is an elevation view partially broken away of a power tool handle mounting a trigger switch embodying the miniature reversing switch of the present invention.

FIG. 2 is a perspective view of the miniature reversing switch in FIG. 1 shown in combination with a known trigger switch.

FIG. 3 is an exploded view in perspective of the miniature reversing switch of FIGS. 1 and 2 constructed in accordance with the present invention.

FIG. 4 is a bottom view of the miniature reversing switch housing illustrating internal structural details with one fixed contact in place.

FIG. 5 is a cross sectional view of the switch illustrated in FIG. 4 taken along line 5-5 of FIG. 4 illustrating the flap in the closed position.

FIG. 6 is a front view of the reversing switch in FIG. 4.

FIG. 7 is a plan view of the contact carrier and knob actuator assembly with the contactor strips in place.

FIG. 8 is a schematic illustration of the tool motor and switching circuit embodying the present invention and illustrating tool motor operation in the "FORWARD" direction of rotation.

FIG. 9 is a schematic illustration of the tool motor and switch circuit embodying the present invention and illustrating tool motor operation in the "REVERSE" direction of rotation.

DETAILED DESCRIPTION OF THE INVENTION

Referring to FIG. 1 of the drawings, there is shown therein a power tool of the portable type indicated generally at 10 having a trigger operated switch 12 incorporating a miniature motor reversing switch 14 constructed in accordance with the instant invention.

The tool illustrated is of the type which incorporates a depending pistol grip handle 16 having switches 12 and 14 mounted therein. Handle 16, which may be formed of cast aluminum or of a rigid high impact plastic material is separable into two sections and is provided with conventionally formed projections or ribs 17 and 18 which entrap switch 12 and with an aperture 22 through which linearly slideable trigger 24 of switch 12 extends. Handle 16 is also provided with a hole 26 in the side wall thereof through which a conventional lock pin 28 of switch 12 extends and is further provided with a hole 30 in the bottom wall thereof through which the insulated power supply leads 32 and 34 extend. Leads 32 and 34 connect switch 12 to a suitable power source (not shown).

The construction and operation of switch 12 is similar to that illustrated and described in H. W. Brown U.S. Pat. application Ser. No. 233,621 filed Mar. 10, 1972 entitled "Butt Contact Speed Control Trigger Switch," now abandoned. As explained therein and shown in FIG. 2 of the drawings, switch 12 includes an insulating base 42, a switch frame 44 for securing trigger 24 to base 42, a lock pin 28 mounted on switch frame 44 and a helical compression spring (not shown) within switch 12 to bias trigger 24 externally of base 42. Upon actuation of trigger 24, contacts (not shown) within switch 12 are bridged closing the circuit to supply current over leads 48, 50, 52, 54 and 56 to energize motor 36.

Having briefly and generally described the construction and operational features of a conventional power tool and a known trigger switch therefor, a unique and inexpensive miniature switching device for reversing the direction of motor rotation by coacting with the aforementioned switch 12 and motor 36 will now be described in more detail with like parts being indicated with like character references throughout the specification and several views.

Referring generally to FIGS. 1 and 2, miniature motor reversing switch 14 is shown mounted atop frame 44 of switch 12. It should be noted at the outset that switch 14 utilizes a very efficient and compact double pole sliding bridge assembly to accomplish the motor reversing function and that such arrangement measures a mere 7/16 inch by 1 1/8 inch dimension by 1/8

inch high, approximately. Further, while a double-pole sliding bridge switching arrangement will be used to illustrate the invention, it will be apparent to those skilled in the art, that the structure disclosed herein can also be used for other types of switches such as a double-pole double throw type or other varieties of single and multi-pole switches.

Referring now in particular to FIG. 3, illustrating the individual reversing switch elements in exploded view, switch 14 is provided with an insulating housing 60 constructed of a suitable electrical insulating material such as a moldable thermoplastic and has pins 62 and 63 molded integral therewith to locate housing 60 in a predetermined position atop frame 44. The pins are received in two holes 64 and 65 during assembly of housing 60 to frame 44 and may either be staked or deformed by heat to firmly secure housing 60 to frame 44.

Internally, housing 60 has a plurality of spaced apart insulating shoulders 66 molded therein as shown in FIGS. 3 and 4 to form recesses or depressions 68 in housing 60 which are adapted to receive and retain individual spring contacts 70, 71, 72 and 73. Contacts 70-73 are constructed of a good electrical conducting material such as copper and are individually secured within depressions 68 adjacent external housing openings 74 near the backside of housing 60 by an integrally hinged cover or flap 76 having an interlocking member 78 in interference fit with shoulder portions 79 in housing 60 upon closure of flap 76 as shown in FIG. 5.

Contacts 70-73 have openings 82 and 83 and lead retainer springs 84 at one end to receive, secure and adjust leads 48, 50, 52 and 54. The lead ends are inserted through openings 74 and 82 and are trapped therein by the retainer springs 84. Stops 91 on flap 76 limit inward travel of the leads through the openings past springs 84. Access depressions 92 including thin penetrable membranes of thermoplastic material are molded integral with housing 60 directly in-line above holes 83 in contacts 70-73 to permit penetration for external manipulation of the retainer springs 84 relative to the leads without having to disassemble switch 14. The membrane serves to shield live electrical conductors from the environment and may be easily plugged after having been pierced.

Contacts 70-73 also have offset conducting portion 93 opposite the lead receiving end of the contacts extending from depressions 68 into slide cavity 80 to engage a sliding contact carrier assembly 95 externally operable through an open ended portion 96 of housing 60.

The carrier assembly 95 is a one-piece thermoplastic molding of generally rigid insulating material having good structural strength such as nylon and includes a slide 98, a flexing hinge 99 and a knurled knob actuator 100.

Slide 98 is provided with a detent projection 101 integrally formed on the side thereof as shown in FIGS. 3 and 7 for interlocking with detent recesses or depressions 102 and 103 in the flexible side wall 104 of housing 60 for releasably securing slide 98 in either forward or reverse modes of operation. Slide 98 also includes an integral stop member 105 bounded by cavity 106 within housing 60 to prevent overtravel of detent projection 101 past depressions 102 and 103.

Slide 98 is further provided with recesses 107 and 108 molded in the topside thereof to receive and secure

contactors 110 and 112 generally flush therewith as shown in FIGS. 6 and 7. Conducting portions 93 are aligned to bear upon and coincide longitudinally of contactors 110 and 112 as shown in FIG. 5 establishing electrical circuit therebetween and to trap the contactors within depressions 107 and 108 upon assembly of switch 14 to frame 44. The bottom side of slide 98 bears against and slides on the top portion 44a of frame 44 and is laterally restrained by cavity sidewall 104 and shoulder 113 of portions flap 76.

Knob actuator 100 includes an abutment or interlock pin 114 integrally molded on the periphery thereof and is adapted for coaction with spaced slots 116 and 118 in the trigger 24, necessitating movement of actuator 100 to either one of the two positions as shown in FIG. 2, to enable the trigger 24 to be depressed or moved inwardly of switch frame 44. It can readily be seen that trigger movement will be blocked for all other actuator positions by the central shoulder portion 120 of trigger 24.

The knob actuator 100 also includes a central bore 122 to permit mounting thereof concentric about the lock pin bushing 123 and extends externally from the side of handle 16 with lock pin 28 in a position to be actuated. It is to be noted that this arrangement requires no additional auxiliary openings in handle 16 and that the existing handle lock pin hole 26 need only be slightly enlarged to accommodate knob actuator 100. Thus, it is readily apparent that rotation of knob actuator 100 about bushing 123 will cause flexing hinge 99 to move contactor slide 98 to bridge selected pairs of contacts 70-73 with contactors 110 and 112 to cause motor 36 to run tool 10 in either the forward or reverse direction of rotation upon actuation of switch 12.

It will be seen, therefore, that for forward rotation of knob actuator 100, as is illustrated in FIG. 8, contacts 70 and 73 are bridged to connect leads 48 and 54 and contacts 71 and 72 are bridged to connect leads 50 and 52. In such position and upon closure of switch 12, current flow is established to motor 36 from switch 12 through lead 48 to contact 70 of switch 14 which is bridged by contactor 110 to contact 73. Current flows therethrough and over lead 54 to motor armature terminal 126 and reenters switch 14 from motor armature terminal 128 through lead 60 to contact 71. The bridging of contacts 71 and 72 by contactor 112 completes the circuit through lead 52 to motor field terminal 130 and back to switch 12 via motor field terminal 132 and lead 56.

Similarly rearward rotation of knob actuator 100 causes shifting of contactors 110 and 112 relative to conducting portions 93 of contacts 70-73 as shown in FIG. 9 to cause motor 36 to run tool 10 in the reverse direction of rotation upon actuation of switch 12. In such position, contacts 70 and 71 are bridged to connect leads 48 and 50. Likewise, contacts 72 and 73 also are bridged to connect leads 52 and 54. As can readily be recognized, this shifting will cause motor 36 to run tool 10 in the reverse direction of rotation upon trigger actuation since the manner of introducing current to armature terminals 126 and 128 has been reversed.

It is to be noted that modification to the carrier assembly 95 for reversing switch 14 hereinbefore described and shown in FIG. 7 may also be made. For example, an elongated reversing lever overlying trigger 24 of the type shown and described in U.S. Pat. No.

3,260,827 to C. J. Frenzel may be molded integral with or mechanically attached to flexing hinge 99 replacing knob actuator 100. Pivoting of such a lever on the top side of housing 60 would, upon actuation, impart linear reciprocal sliding motion to slide 98 through hinge 99. Moreover, thumb actuated levers of the type described and shown in U.S. Pat. No. 3,376,402 to T. E. Bednarski may also replace knob actuator 100 and be pivoted on the top side of housing 60 to operate slide 98.

From the foregoing, it will be apparent to those skilled in the art, that the present invention provides a substantial improvement in reducing the number of component parts for reversing switches for power tools and appliances. It will also be readily recognized that such reduction of parts coupled with the unique arrangement and interaction of those utilized provides a highly efficient and durable miniature switch which is inexpensive to manufacture and readily adaptable to existing tools without the need for extensive or expensive tool handle modifications or for additional complicated wiring during the assembly stage of such tools.

While the apparatus hereinbefore described is effectively adapted to fulfill the objects stated, it is to be understood that the invention is not intended to be confined to the particular preferred embodiment of the miniature motor reversing switch disclosed, inasmuch as it is susceptible of various modifications without departing from the scope of the appended claims.

I claim:

1. In combination, a power tool comprising:
a tool housing;
motor means mounted therein;
switch means on said tool for energizing said motor
means in forward and reverse operation modes;
lock means on said tool for locking said switch means
in selected positions of actuation; and,
wherein said switch means further includes actuator
means having a portion of which is mountable on
said lock means exposing a portion of said lock
means to permit independent operation of each,
said actuator means being operable with said
switch means to cause said motor means to operate
in either a forward or reverse operating mode.

2. A tool according to claim 1 wherein said switch
means comprises a first switch for energizing said
motor means and a second switch including said actuator
means for selecting the operating mode, wherein
said lock means is operatively connected to said first
switch, and wherein said second switch is in circuit and
operatively connected to said first switch.

3. A tool according to claim 1 wherein said lock
means includes a lock pin bushing and a lock pin ex-
tending generally laterally of said housing, wherein said
actuator means is a cylindrical knob having a central
bore for mounting concentrically about said lock
means for movement relative thereto and wherein said
lock pin extends through said bore to permit inde-
pendent operation thereof relative to said actuator means.

4. A trigger switch for a power tool, the switch com-
prising:
an insulating frame;
switch means in said frame having a trigger actuator
which is operable, upon actuation, to energize a

tool;
lock means mounted transversely of said frame and
operable to lock said trigger actuator in selected
positions of actuation; and

5. wherein said switch means further includes actuator
means having a portion of which is mountable on
said lock means exposing a portion of said lock
means to permit independent operation of each,
said actuator means being operable with said
switch means to cause reversal of operating power
to a power tool.

5. A trigger switch according to claim 4 wherein said
lock means includes a lock pin bushing and a spring bi-
ased lock pin extending therethrough and generally lat-
erally of said frame, wherein said actuator means is a
cylindrical knob having a central bore for mounting
concentrically about said lock means for movement
relative thereto and wherein said lock pin further ex-
tends through said bore to permit independent opera-
tion thereof relative to said actuator means.

6. A trigger switch according to claim 4 wherein said
trigger actuator further includes a plurality of slots and
shoulders formed on a side face thereof, wherein said
actuator means further includes interlock means which
coact with said slots and shoulders to prevent said
actuator means from being actuated to reverse power
through said switch while said trigger actuator is in an
actuating state.

7. A trigger switch according to claim 4 wherein said
switch means further comprises:

switching means within a housing mounted on said
frame being operable when energized to power said
power tool in either a forward or reverse operating
mode, said switching means comprising:

a plurality of fixed contacts within said housing;
contactor means adapted to conductively bridge se-
lected fixed contacts to cause reversing of current
through said switching means to said tool; and,
carrier means for operating said contactor means
comprising:

slide means for supporting said contactor means in
bridging relationship with said fixed contacts; and

hinge means interconnecting said slide means and ac-
tuator means and being responsive to move said
slide means in response to movement of said ac-
tuator means.

8. A switch according to claim 7 wherein said lock
means includes a lock pin bushing and lock pin extend-
ing generally laterally of said frame, wherein said actuator
means is a generally cylindrical knob having a central
bore for mounting concentrically about said lock
means for relative movement to said actuator means.

9. A switch according to claim 7 wherein said fixed
contacts have resilient retainer means for securing lead
means thereto and wherein said housing has access
means adjacent said contacts to permit adjustment of
said retainer means relative to said lead means without
having to disassemble said reversing switch.

10. A switch according to claim 7 wherein said car-
rier means is an integral one-piece thermoplastic
mounting.
